ANTICAPACITY THERMIONIC TUBE

Frederick S. McCullough, Pittsburgh, Pa., assignor to The Union National Bank of Pittsburgh, Pittsburgh, Pa.

Application July 17, 1926; Serial No. 123,086
Renewed January 18, 1932

6 Claims. (Cl. 250—27.5)

This invention relates to thermionic tubes and more particularly to tubes of the so-called three-element type wherein there is employed in addition to a hot cathode, a plate or anode and a grid or control electrode.

It has been recognized for some time that in a tube of the ordinary three-element type there is a capacity relation between the grid or control electrode and plate. This capacity relation is detrimental to the functioning of the tube in certain circuits by reason of the fact that it serves to effectively by-pass a considerable portion of the radio-frequency currents employed on the grid. It is also detrimental in certain circuits by reason of the fact that it sustains regeneration in the tube with a consequent distortion of signals.

Efforts have been made to overcome this capacity effect by the use of external capacities acting in opposition to the capacity existing between the grid and the plate and commonly referred to as neutralizing condensers. One difficulty with the use of external neutralizing circuits is that the neutralizing capacity must be very delicately adjusted, and this adjustment is not only easily disturbed but due to the non-uniform characteristics of the tubes, may be correct for one tube and not for another tube. It is, of course, impractical to vary this delicate adjustment every time the tube is changed, so that external neutralization is not universally satisfactory for this reason. Another difficulty with externally neutralized circuits arises from the capacity relation existing between different wires that form the circuit, so that excessive neutralizing capacity is introduced into the circuit and this effectively reduces the amplifying action of the tube.

The present invention proposes to provide a tube wherein there is no capacity relation between the grid and the plate so that external neutralization need not be resorted to.

The nature of the present invention may be readily understood by reference to the accompanying drawing which illustrates one embodiment of my invention and in which:

Figure 1 is a diagram of the tube;

Figure 2 represents a transverse vertical section through an assembled tube;

Figure 3 is a similar section at right angles to Figure 2, the enclosing envelope not being shown in this figure;

Figure 4 is a section in the plane of line IV—IV of Figure 2.

Figure 5 is a vertical section showing the grid and anticapacity element in elevation; and

Figure 6 is a transverse section through the structure shown in Figure 5.

The nature of the invention may be generally described in connection with the diagram shown in Figure 1. The diagram indicates a tube which has four contact pins in the base thereof to conform to standard practice. The first pin, number 2, leads directly to the grid 3. Pins 4 and 5 connect with the cathode or filament 6. Pin 7 connects to the mid-point of a coil 8 built into the tube structure. One end 9 of the coil 8 connects with the plate or anode 10. The other end 11 of the coil connects with an anti-capacity element 12 built into the tube structure and bearing the same relation to the plate 10 that the grid 3 has. The grid 3 and the anti-capacity element 12 each are of approximately the same length and have substantially the same surface area. Each of them is disposed the same distance from the plate and the positions of each with respect to the plate are substantially identical. Neither is nearer to the plate than the other and they both occupy substantially the same position in the tube between the cathode and the plate. The anti-capacity member 12 preferably is coated with a heat resistant insulation so as to minimize to the greatest possible extent any flow of current between it and the hot filament.

It will be apparent to those skilled in the art that since the plate 10 and the anti-capacity element 12 are at opposite ends of the winding 8, and since this winding 8 is tapped at its mid-point that, while both the plate and the anti-capacity element will have a positive potential with reference to the direct current applied to the anode in the usual manner, the anti-capacity element will have a potential opposite to that of the anode 10 with reference to radio-frequency oscillations in the tube circuit. Frequently the anti-capacity element will tend to destroy the capacity relation existing between the grid 3 and the plate 10 thereby providing an internally neutralized tube.

In the practical embodiment of the invention, the tube will have an envelope 13 in which is the usual stem 14 and which is secured, in the usual manner, in a base 15. The pins 2, 4, 5 and 7 are arranged in the base 15 in accordance with the usual practice. The filament 6 is supported in the tube in accordance with present practice, being carried on wires 6a and 6b which pass through the stem 14. The grid 3 and anti-capacity element 12 are carried around spaced apart parallel porcelain or other refractory non-con-

ducting rods 16. The rods 16 are supported on wires 17 and 18 which pass through the stem 14. Wrapped about the rods 16 in parallel relation are wires 3 and 12 providing the grid and the anti-capacity elements respectively. The rods 16 are preferably notched or grooved to retain the wires in proper spaced relation out of contact with each other. For the purpose of illustration, I have indicated the cross-section of the grid wire 3 as an open section and the cross-section of the anti-capacity wire 12, which is insulated in solid black. This is for the purpose of convenience. The rods 16, which preferably have openings extending therethrough are braced at the top by an inverted U-shaped wire 19, the legs of this wire extending down into the rods but being separated from the upper ends of the respective wires 17 and 18. The grid 3 is connected with the wire 17 and the anti-capacity element 12 is connected with the wire 18. The plate 10 is in the form of a flat sheet at each side of the structure formed by the two rods 16 and the associated elements 3 and 12 and is carried on a wire 20 passing through the stem of the envelope. It will be seen that filament 6 is inside the cage provided by the wires 3 and 12 and the supporting rods 16. The plate 10 is equally spaced from the wires 3 and 12 and these wires occupy substantially the same relative position between the filament and the plate. The surface areas of both wires are the same, so that neither has a capacity effect greater than the other.

Inside the base 15 and below the envelope is an inductance coil 8. This coil may be disposed around the lead wires through the base in such manner as not to interfere with the assembly of the tube and can be of such a size as will give the best results in the use. The plate lead wire 20 connects to one side of this coil while the pin 7 in the base connects to an intermediate point thereof. The lead wire 18 connecting to the anti-capacity element 12 is in circuit with the other end of this coil, in accordance with the diagram shown in Figure 1.

The operation of the tube is in substantially all respects similar to the operation of the ordinary three-element tube, the chief difference being that the anti-capacity element 12 serves to eliminate any capacity effect between the grid and the plate. This reduces the tendency of the tube to oscillate and makes it particularly useful in amplification circuits, especially circuits for effecting amplifications for radio-frequency circuits. By reason of the anti-capacity element 12 being coated with an insulating material, it will not actively function as an electrode to divert the electron current between the plate and the cathode.

Since the capacity effect between the grid and the plate is eliminated, there is no need for external neutralization of the circuit in which the tube is employed, and the characteristics of the circuit will not be materially changed by the substitution of one tube for another. In many circuits where an attempt is made to neutralize the internal capacity of the tube by an external means, the circuit is made unstable by the substi-

tution of one tube for another, thereby introducing practical difficulties into this method of avoiding internal capacity effects.

The manufacture of the tube can be accomplished in accordance with present methods and 80 the tube degassed in the usual manner.

In the form of tube shown in Figures 5 and 6, the same reference numerals designate corresponding parts, except that the reference numerals have a "prime" mark applied thereto. 85 In this form the anticapacity element 12' is disposed outside the grid and adjacent thereto, and is formed of vertically arranged insulated wires.

While I have illustrated a specific embodiment 90 of my invention, it will be understood that this is merely by way of illustration, and I do not limit myself to the particular construction and arrangement shown, as the invention may be otherwise embodied within the contemplation of my invention.

I claim:

1. A thermionic tube having a cathode, a plate, a grid, and an anti-capacity member in the tube, an inductance in the base of the tube having one end connected to the anti-capacity element and 100 having its other end connected with the plate, and a central tap for the inductance.

2. An electron tube having a cathode, an anode, and a grid, an anti-capacity member in the tube in proximity to the grid, and an inductance 105 connecting the plate and the anti-capacity member, said inductance having a central connection therein through which a direct current potential may be applied to the anode.

3. A thermionic tube including an envelope, a 110 base for the envelope, a cathode, a plate, a grid, and an anti-capacity element, said cathode, plate, grid, and anti-capacity element being within the envelope, and an inductance in the base outside the envelope, said inductance being connected at 115 one end to the anti-capacity element and being connected at its other end to the plate and a terminal in the base connected to an intermediate point of the inductance, said base also having contact terminals leading to the cathode and 120 the grid.

4. A thermionic tube having therein a plate, a cathode, a grid, and an anti-capacity element having insulation thereon, said plate and anti-capacity element being connected in out-of-phase 125 relation with each other.

5. A thermionic tube mount including a grid supporting element comprising a post formed of insulating material and having a plurality of notches therein, and a wire entered in one end 130 of the post and supported by the tube for holding the post in a fixed position.

6. A grid structure for thermionic tubes comprising a plurality of parallel posts of insulating material having a series of peripheral notches 135 therein, and a pair of conductors wrapped about and supported by the posts, the wires setting in the notches and being maintained in spaced relation thereby, one of said conductors constituting a grid and the other a shielding electrode.

140

FREDERICK S. McCULLOUGH.
